UNITED STATES PATENT OFFICE

CARL F. BURCK, OF BUFFALO, NEW YORK

TRANSFER SAFETY DEVICE

Application filed April 22, 1932. Serial No. 606,921.

This invention relates to a device for safely transporting valuables and has for the primary object, the provision of an armored vehicle having means operable from therein whereby valuables may be easily and quickly transferred from the vehicle to the interior of a building or vice versa with complete safety against theft or robbery and without subjecting the operator to fire arms in the hands of bandits.

With this and other objects in view, this invention consists in certain novel features of construction, combination and arrangement of parts to be hereinafter more fully described and claimed.

For a complete understanding of my invention, reference is to be had to the following description and accompanying drawings, in which

20 Figure 1 is a side elevation partly in section illustrating an armored vehicle with a valuable handling means mounted therein and constructed in accordance with my invention.

25 Figure 2 is a fragmentary vertical sectional view illustrating the same and showing the valuable handling means extending through the wall of the building to permit transfer of the valuables either from the building to the vehicle or from the latter to the building.

Figure 3 is a horizontal sectional view taken on the line 3—3 of Figure 2.

30 Figure 4 is a detail transverse sectional view taken on the line 4—4 of Figure 2.

Figure 5 as a similar view taken on the line 5—5 of Figure 2.

35 Referring in detail to the drawings, the numeral 1 indicates a motor vehicle carrying an armored body 2 provided in the rear end thereof with an opening 3 for the purpose of permitting valuables to be transferred either from the body to a building or from the latter to the body. The wall of a building is shown at 4 and is provided with a receiving opening 5 so that when the vehicle is backed up to the wall, the opening 5 will align with the opening 3. Wear plates 6 may be positioned about the walls of the opening 5.

40 A mounting 7 is suitably secured in the ar-

mored body and slidably supports a piston 8. One end of the piston is cut away to form a strong box 9 closed by a cover 10. A concealed hinge 11 is employed for connecting the cover 10 to the strong box 9 and said cover upon its inner face has an extension 12 to which a link 13 is pivoted. The other end of the link 13 is pivoted to an operating rod 14 slideable in a bore of the piston and having threaded connection with a feed nut 15. The feed nut 15 at one end is provided with a suitable handle 16 for imparting rotation thereto and is journaled within the piston. An annular groove 17 is formed in the nut 15 to receive the inner ends of set bolts 18 carried by the piston for the purpose of rotatably securing the nut in the piston. The set bolts 18 are carried by the piston with their outer ends so arranged as not to interfere with the sliding movement of the piston within the mounting.

45 From the foregoing it will be seen that by rotating the handle 16 in one direction, the cover 10 will be opened and when rotated in an opposite direction, the cover will assume a position for closing the strong box 9.

50 Supports 19 are secured in the armored body and have journaled thereto a feed screw 20 meshing with a feed nut 21 carried by the piston 8 and operating within a slot 22 of the mounting. A crank handle 23 is secured to one end of the feed screw 20 whereby the same may be conveniently rotated in either direction for the purpose of moving the piston into and out of the armored body 55 and when moved inwardly the end of the strong box 9 is adapted to form a closure for the opening 3.

55 In operation, the vehicle is backed against the wall 4, the pavement being provided with recesses 24 to receive the rear wheels of the vehicle so as to act as a guidance to the operator of the vehicle for aligning the opening of the armored body with the opening 5 of the building. The operator confined within the armored body places the valuables in the strong box 9 and rotates the crank handle 23 in a proper direction to feed the piston outwardly and through the opening 5 of the building. The operator then rotates the 60

handle 15 in a proper direction to open the cover 10 so that a second operator within the building may remove the valuables and thereby obviate any possibility of theft of the valuables during the transferring of the same from the armored body to the building or vice versa.

While I have shown and described the preferred embodiment of my invention, it 10 will be understood that minor changes in construction, combination and arrangement of parts may be made without departing from the spirit and scope of my invention, as claimed.

15 Having thus described my invention, what I claim is:—

1. A device for transporting valuables comprising an armored motor vehicle body having an opening, a strong box slidably 20 mounted in the body, means operated from the interior of the body to slide the strong box through the opening into a building, and means for opening and closing the strong box from the interior of the body.

25 2. A device for transporting valuables comprising an armored vehicle body having an opening, a mounting located in the body and aligning with the opening, a piston slid- 30 able in said mounting, a strong box carried by the piston, means for sliding the piston in either direction from within the body, and means for opening and closing the strong box from within the body.

35 3. A device for transporting valuables comprising an armored vehicle body having an opening, a mounting in said body align- 40 ing with the opening, a piston slidable in said mounting and movable through the opening and normally occupying a position to close the opening, a strong box formed 45 integrally with the piston, a hinge cover for the strong box, an operating means located within the body and connected to the cover for opening and closing the strong box, and means for imparting sliding movement to the piston.

50 4. A device for transporting valuables comprising an armored vehicle body and having an opening, a mounting in said body and aligning with the opening, a piston slid- 55 able in the mounting and movable through the opening, a strong box formed integrally with the piston and movable outwardly of the body by said piston, a hinge 60 cover for said box, an operating rod journaled to the piston, means connecting the rod to the cover, a feed nut journaled to the piston and located within the body to permit manual opening and closing of the cover when the box is located interiorly or exteriorly of the body, and means for im- 65 parting sliding movement to the piston in either direction from the interior of the body.

65 5. A device for transporting valuables

comprising an armored vehicle body having an opening, a mounting in said body and aligning with the opening, a piston slidable in the mounting and movable through the opening, a strong box formed integrally with the piston and movable outwardly of the body by said piston, a hinge cover for said box, an operating rod journaled to the piston, means connecting the rod to the cover, a feed nut journaled to the piston and located within the body to permit manual opening and closing of the cover when the box is located interiorly or exteriorly of the body, a worm feed shaft journaled in the body, a nut meshing with the worm feed 70 shaft and secured to the piston, and a handle secured to the shaft and located in the body to permit a person therein to impart movement to the piston in either direction. 75

80 In testimony whereof I affix my signature. 85
